COMBINED HOLDER AND DISPENSER FOR CASSETTES, CARTRIDGES AND THE LIKE

William P. McRae, 19969 Acre St.,
Northridge, Calif. 91324

Filed Apr. 14, 1972, Ser. No. 244,351

Term of patent 14 years

Int. Cl. D6—04

U.S. Cl. D6—188

FIG. 1 is a perspective view of a combined holder and dispenser for cassettes, cartridges and the like embodying my new design;

FIG. 2 is a front elevational view thereof;

FIG. 3 is an end elevational view thereof, both ends being the same;

FIG. 4 is a rear elevational view thereof; and

FIG. 5 is a bottom plan view thereof.

I claim:

The ornamental design for a combined holder and dispenser for cassettes, cartridges and the like, as shown and described.
